UNITED STATES PATENT OFFICE.

EMIL KASELOWSKY, OF BERLIN, GERMANY.

APPARATUS FOR LAUNCHING TORPEDOES.

SPECIFICATION forming part of Letters Patent No. 361,526, dated April 19, 1887.

Application filed February 4, 1887. Serial No. 226,546. (No model.)

To all whom it may concern:

Be it known that I, EMIL KASELOWSKY, a subject of the King of Prussia, residing at Berlin, in the Kingdom of Prussia, German Empire, have invented new and useful Improvements in Launching Attachments for Torpedo-Tubes, of which the following is a full, clear, and exact description.

The object of the invention is to provide an attachment for the temporary inclosing case or tube of nautical torpedoes, whereby the torpedo may be guided in its exit from the said case or tube in being launched until it has entirely left the same to take the water.

15 The invention consists in a bar or beam that may be extended outward from the torpedo case or tube and provided in its bottom side with a suitable guide that substantially conforms to a guide stud or projection on the 20 outer surface of the torpedo, so that as the torpedo leaves the tube or case the projection thereon will enter the slot in the guide-bar, and the torpedo thus be supported and guided until it has entirely emerged from its tube, when 25 it will glide into the water, as will be herein-after more particularly described, and pointed out in the claims.

Reference is to be had to the accompanying drawings, forming a part of this specification, 30 in which similar letters of reference indicate corresponding parts in all the figures.

Figure 1 is a longitudinal sectional elevation showing the torpedo with its inclosing-case and my improvement in full lines, and 35 also showing in dotted lines the torpedo just as it has completely emerged from the tube. Fig. 2 is a plan view of the inclosing-tube and its guide-bar. Fig. 3 is an enlarged cross-section.

40 As the preferred arrangement and construction of my invention, I have shown the torpedo-holding case or tube A as constructed with a box, chamber, or compartment, a, on the top thereof. Sliding longitudinally in this 45 compartment a is the bar d, having rack-teeth on its upper surface. The bar d, when provided with rack-teeth, as shown, is drawn into or out of the box, either partly or all the way, as may be desired, by means of a pinion, as at 50 f, and a crank-handle, as g, or other equivalent means.

In the bottom of the bar d is formed a longitudinal guide-slot, m, of a form to correspond with the projection or stud p on the torpedo B. The guide-slot m and stud or pro-

jection p may be of any form that will allow the stud p to enter and be disengaged from the guide-slot m only at the ends of the guide-bar—that is to say, of such a form that the stud p cannot enter the slot m nor be disengaged therefrom at any point intermediate the ends of the bar d.

Although I have shown the said slot and stud of T shape, it will be understood that other forms might be employed. For instance, 65 the stud may have a rounded head and the slot be of a form to correspond.

Binding-screws n n are provided in the box a, to lock the bar d in its extended position.

When the bar d is completely within the 70 case, the same slide or cover that closes the torpedo proper will also close the front end of the box or compartment a.

It will be seen that by the use of the above-described invention the torpedo will be safely 75 and easily guided in its exit from the tube until it has completely emerged from the same to take the water.

With the exception of being provided with the stud p, the torpedo may be of any ordinary 80 or approved construction.

The bar d, it is evident, may be operated by means other than a rack and pinion, as stated.

Having thus fully described my invention, I claim as new and desire to secure by Letters 85 Patent—

1. A torpedo case or tube provided with a guide-bar adjustable relatively to said tube and slotted in its bottom side, in combination with a torpedo having a guide stud or projection adapted to said slot, substantially as described.

2. In combination with a torpedo-tube, a bar adjustable longitudinally of said tube and formed throughout its length with a slot T-shaped in cross-section, substantially as shown and described.

3. The combination, with a torpedo-tube and a longitudinally-adjustable bar thereon, the latter having a longitudinal guide-slot of substantially T shape in cross-section, of a torpedo having a headed guide-stud adapted to said slot, substantially as shown and described.

In testimony whereof I have signed my name to this specification in the presence of two subscribing witnesses.

EMIL KASELOWSKY.
